(57) **CLAIM**

The ornamental design for a refrigerator, as shown and described.

DESCRIPTION

FIG. 1 is a front perspective view of a refrigerator, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of a door portion thereof;

FIG. 9 is a front view of the door portion thereof;

FIG. 10 is a rear view of the door portion thereof;

FIG. 11 is a left-side view of the door portion thereof;

FIG. 12 is a right-side view of the door portion thereof;

FIG. 13 is a top view of the door portion thereof;

FIG. 14 is a bottom view of the door portion thereof;

FIG. 15 is an enlarged view of the portion 15 in FIG. 8;

FIG. 16 is a partially enlarged cross-sectional view of the door portion thereof, taken along line 16-16 in FIG. 9; and, FIG. 17 is a partially enlarged cross-sectional view of the door portion thereof, taken along line 17-17 in FIG. 9.

The even-dash broken lines illustrating portions of the refrigerator form no part of the claimed design. The dot-dot-dash broken lines encircling enlargement portions of the refrigerator form no part of the claimed design.

1 Claim, 17 Drawing Sheets
